UNITED STATES PATENT OFFICE.

ERNST AUGUST KROENKE, OF NEW YORK, N. Y.

REFRIGERATOR.

No. 919,030.

Specification of Letters Patent.

Patented April 20, 1909.

Application filed October 20, 1905, Serial No. 283,567. Renewed February 4, 1909. Serial No. 476,098.

To all whom it may concern:

Be it known that I, ERNST AUGUST KROENKE, a citizen of the United States, residing in New York, borough of Brooklyn, and State of New York, have invented certain new and useful Improvements in Refrigerators, of which the following is a specification.

This invention relates to improvements in refrigerators and more especially to refrigerators which are intended for the use of grocers and liquor dealers, for storing different articles in a number of compartments, and in which they are stored in such a manner that quick, convenient and easy access in each compartment is obtained; and for this purpose the invention consists of a refrigerator, the main body of which is rotatable around an upright center post attached to a suitable platform, the refrigerator being of polygonal shape and provided with an ice-chamber in the upper part, storage-chambers around the ice-chamber, drip-pans for the ice water below the bottom of the ice-chamber, additional storage-chambers arranged around the drip-chamber, the storage chambers being provided with sliding outer doors and sliding inner doors connected therewith so as to open the opening of the drip-chamber when the sliding doors are closed, and a provision-chamber in the lower part of the refrigerator.

The invention consists of additional details of construction which will be more fully described hereinafter and finally pointed out in the claims.

In the accompanying drawings, Figure 1 represents a vertical section of my improved refrigerator, Fig. 2 is a plan view partly in horizontal section on line 2—2 Fig. 1, and Fig. 3 is a section on line 3—3 on Fig. 1.

Similar letters of reference indicate the same parts in the different figures of the drawings.

Referring to the drawings, *a* represents a suitable platform which is permanently attached to the floor. In the center of the platform *a*, is attached an upright post or column *b*, preferably made of cast-steel. By means of anti-frictional bearings, a refrigerator body or casing *R* of cylindrical or polygonal shape and of suitable height, which is provided at its center with a sheet metal tube *t* can rotate freely on the platform around the center post, so as to give access to any compartment of the same. The ice-

chamber *i*, is arranged at the upper central part of the refrigerator, it being filled through openings which are closed by means of hinged doors *G*, the compartments adjacent the ice-chamber being like-wise closed by means of hinged doors *G*¹. On both sides of the ice-chamber and the charging compartments are arranged additional storage-chambers *C* which connect by openings at the inner ends with the ice-chamber and are closed by outer hinged doors. These storage chambers are used for storing milk, wines and similar articles.

Below the slotted bottom *B* of the ice-chamber, is arranged a drip-chamber *D* in which are located inclined shelves *d*, and an annular trough *d*¹, which is arranged around the central sleeve inclosing the center post and from which the drip-water is conducted by means of a drip-tube *d*² to the bottom of the refrigerator where a receptacle *d*³ is provided.

The ice water which drops through the slotted bottom of the ice-chamber cools the delivery shelves as well as the trough, and thereby the air ascending from the lower or provision-chamber is cooled and keeps the refrigerator at a low temperature. This air, which ascends from the lower provision-chamber, passes upwardly into the drip-chamber *D* and then into the ice-chamber.

Around the drip-chamber *D* are arranged compartments *C*¹ which are closed by means of sliding doors *F*, that are guided in ways of the outer frame of the refrigerator. The sliding doors *F* are connected by inclined bracket rods *f* with interior doors *F*¹ which move over the openings in the walls of the drip-chamber when the doors *F* are raised for giving access to the compartments *C*¹ and which are lowered when the doors *F* are moved to close the compartments. The bracket-rods *f* are arranged on both sides of the sliding-doors in such a manner as to connect the lower part of the same with the upper parts of the inner doors *F*¹ so that bracket-rods *f* do not interfere with the tubs of butter or other articles stored in the compartments *C*¹. The connection between the outer doors and the inner doors has the advantage that when the charge-doors are opened, the supply of cold air from the drip-chamber into the compartments *C*¹ is shut off, while when the outer doors are closed, the supply of cold air to the compartments *C*¹ is restored, and thereby these compartments retained at a

lower temperature notwithstanding the fact that they are subject to being frequently opened to give access to articles stored therein.

5 The lower compartment C² under the drip-chamber, which compartment is divided off from the compartments C¹ by a horizontal wall or partition J, is used as a provision-chamber for storing articles or butter tubs, so 10 as to have them ready for use when the butter in the tubs placed in the compartments C¹ is sold. The provision-chamber may, of course, be used also for the storing of other articles. The chamber is provided with hinged 15 doors H along its sides so as to give access to all parts of the chamber. The annular space between the compartments may be used for arranging electric lights in same, as indicated by dotted lines in Fig. 2, so as to light up the 20 part of the refrigerator from which things are to be taken, by simply pressing a switch in the outer side of the refrigerator. The panels that are formed in the frame of the refrigerator are provided with colored glass 25 panes so as to throw the light of the incandescent lights to the outside. If desired, all lights may be kept burning so that the refrigerator can be rotated for moving the articles from the different compartments, the lighted 30 up interior facilitating the removal of the articles and the replacing of the same with a new supply. The exterior walls of the refrigerator are made double and filled with non-conductor of heat as is customary in construction of refrigerators.

35 The advantage of my improved rotatable refrigerator is that any of the compartments are accessible from a certain point without having to run around the refrigerator, as the 40 same can be readily turned by the attendant to bring any desired part of the refrigerator within reach. By a central arrangement of the ice-chamber and drip-chamber, the cold air is distributed to all the chambers and 45 compartments of the refrigerator so as to establish a uniform temperature therein, and the escape of the cold air from the drip-

chamber to the outside is prevented by means of the sliding doors arranged in connection with the middle compartments.

50

Having thus described my invention, I claim as new and desire to secure by Letters Patent.

1. In a refrigerator, the combination of a casing having a central ice-chamber located 55 in the upper part thereof, walls defining storage-chambers arranged around said ice-chamber, walls dividing the middle part of said casing into a drip-chamber below said ice-chamber and compartments surrounding 60 said drip-chamber, there being openings in the exterior walls of said compartments and in the walls of said drip-chamber, doors to close the openings of the compartments, doors to close the openings of the drip-chamber, means for connecting said doors so that one is opened when the other is closed, and a wall or partition which divides said compartments from the lower part of the casing 65 and forms a provision chamber below the 70 drip-chamber and said compartments.

2. In a refrigerator, the combination of a casing having an ice-chamber at the upper part, upright walls dividing the middle part of said casing into a drip-chamber below said 75 ice-chamber, and compartments surrounding said drip chamber, the walls of said drip-chamber and the exterior walls of said compartments being provided with openings, sliding doors movable over said openings of 80 the drip-chamber and compartments, and means for connecting the doors of the compartments with the doors of the drip-chamber, whereby the corresponding door of the drip-chamber is closed when each compartment door is opened, and vice versa.

In testimony, that I claim the foregoing as my invention, I have signed my name in presence of two subscribing witnesses.

ERNST AUGUST KROENKE.
